UNITED STATES PATENT OFFICE.

CORNELIUS HOOD, OF CLEVELAND, OHIO.

COMBINED STEP-LADDER AND WASH-BENCH.

SPECIFICATION forming part of Letters Patent No. 257,493, dated May 9, 1882.

Application filed October 22, 1881. (No model.)

To all whom it may concern:

Be it known that I, CORNELIUS HOOD, of Cleveland, in the county of Cuyahoga and State of Ohio, have invented certain new and useful Improvements in Step-Ladders, of which the following is a specification.

The nature and objects of these improvements will fully appear from the subjoined description, when considered in connection with the accompanying drawings, in which—

Figure 1 shows the step-ladder. Fig. 2 shows the step-ladder arranged as a wash-bench. Fig. 3 shows the step-ladder closed when not in use. Fig. 4 is a rear view of the ladder, showing the brace D.

The objects of the invention are the combination of a step-ladder and a wash-bench in one device.

A represents the step portion of the step-ladder, and B the hinged support.

The brace C, connecting the said parts of the step-ladder, and which forms the first of my improvements, consists of two iron bars of peculiar construction. Each of said bars is made one-half thickness in about half its length, and the two are pivoted together at the middle of the said half-thickness, thus forming a joint for folding the said brace together when the ladder is closed. The ends of the thin portion are beveled off, so that when the brace is opened the said beveled ends fit into dovetail shoulders e in the thick portion. This is for the purpose of preventing the brace from folding downward, and also helps to stiffen the brace when open.

The sliding brace D for supporting the shelf, which forms the second of my improvements, consists of a flat bar, D, attached to a cross-

bar, d, having its ends journaled in the arms of the shelf, thus enabling the said bar to oscillate as the shelf is raised or lowered. The lower end of said brace D slides through a mortise in a similar oscillating cross-bar, d², journaled in the support B. The lower end of said support D is provided with a spring-catch, d³, for retaining the bar in place and holding the shelf up. When it is desired to close the shelf the spring is depressed.

The third of my improvements consists in making a shoulder, e, on the inner ends of the arms of the shelf E and of the legs of the supporting-frame F, so that when said frames are turned into position for forming the wash-bench the upper and lower steps of the ladder A rest in said shoulders e aforesaid. This relieves the bolts from the strain which they would otherwise be subject to, and thus the bench is made extra strong and stiff, capable of sustaining much greater weight, and is not liable to wrenching or loosening of the joints.

Having described my invention, I claim—

1. The combination, with the support B and the hinged shelf E, of the sliding brace D, attached to the cross-bar d, journaled in the arms of the shelf and playing in a mortise in the oscillating cross-bar d², and provided with the spring d³, all as shown and described.

2. The combination, with the step-ladder and its support B, of the frames E and F, having the notches or shoulders e e in their upper ends, which engage with the edges of the steps, as and for the purpose set forth.

C. HOOD.
